UNITED STATES PATENT OFFICE.

WILLIAM C. KIDD, OF SUFFERN, NEW YORK, ASSIGNOR TO STANDARD EQUIPMENT COMPANY, OF MAHWAH, NEW JERSEY, A CORPORATION OF NEW JERSEY.

SWITCH STAND.

Application filed June 14, 1921, Serial No. 477,380. Renewed July 18, 1922. Serial No. 575,823.

To all whom it may concern:

Be it known that I, WILLIAM C. KIDD, a citizen of the United States, and resident of Suffern, in the county of Rockland and 5 State of New York, have invented certain new and useful Improvements in Switch Stands, of which the following is a specification.

This invention relates to railway switch 10 stands, and particularly to the means for holding the interlocking portions of a switch stand against accidental disengagement.

Switch stands of the type shown in the drawings are usually known as "Ramapo" 15 switch stands and comprise means permitting and controlling automatic throwing of the switch points by a trailing locomotive or car in combination with means for operating the switch manually independently of the 20 automatic means, the said automatically operated means and manually operated means being normally interlocked except during the period when the switch points are being thrown manually.

25 The present invention relates particularly to means for yieldingly holding the automatic means and the manually actuated means in locking engagement and for preventing accidental disengagement thereof 30 from jars or concussions due to passing trains or other causes.

A further object of the invention is to provide means whereby the switchman may be apprised when the switch point is thrown 35 into its operative position in contact with the running rail and the moving parts of the switch stand interlocked.

A further object of the invention is to provide an enclosed mechanism which will 40 be secure against accidental misplacement and protected against malicious tampering.

Still another object of the invention is to provide a simple, compact and self-contained mechanism which will hold the interlocking 45 parts under yielding pressure, readily permitting manual operation of the switch but preventing accidental movement sufficient to disengage such parts.

Various other objects of the invention will 50 be more fully set forth in the following description of one form of switch stand embodying my invention shown in the accompanying drawings, in which:

Figure 1 is a view in perspective of a 55 switch stand embodying my invention;

Figure 2 is a plan view of the switch stand, the automatic safety control mechanism being indicated in dotted lines;

Figure 3 is a detailed view, partly in section, of a portion of the switch stand. 60

It will be understood that this invention is applicable to switch stands of various types and designs, but for purposes of illustration the invention is shown as applied to the switch stand described in detail in 65 Patent No. 882,024, granted March 17, 1908, to F. W. Snow and myself as joint inventors. In this switch stand the spindle 1, which may carry a lamp or a target or other signal, is rigidly connected to the switch 70 points preferably through a screw eye 2 by means of a connecting rod fastened to the switch points (not shown). The safety device, or means for controlling automatic movement of the switch points is housed 75 within a frame or casing 3 forming the base of the switch stand, and comprises a bearing block 4 provided with a central bearing within which the spindle is freely rotatable.

The bottom of the block 4 is provided with 80 a star member 5 which is always in engagement with oppositely disposed rollers 6. Said rollers are mounted in yokes or frames and yieldingly held in engagement with the star member by springs 7. The arrangement of these parts is such that any movement of the block will compress the springs which will automatically tend to return the block to its original position until the points of the star member pass the center line of the 90 rollers, whereupon the action of the springs will tend to rotate the block further and in the same direction until the rollers again come to rest intermediate the star points, thereby throwing and holding the switch 95 point against the running rail.

The upper part of the star or bearing block projects above the top of the housing and is provided with squared sockets 8. An arm 9 is pivoted as at 9² to a block 10 rigidly secured to or formed integral with the spindle so as to have vertical movement with respect to the spindle. The bottom of this arm is adapted to seat in the sockets 8 thereby interlocking the automatic control means 105 with the manually operated means. The arm projects a suitable distance beyond the star block and may be operated manually or it may be operated by means of the cam lever 11 pivoted as at 12 to the base. The 110

cam surface of this lever is so designed that a movement of the lever in a single plane parallel to the track will raise the arm from one of the sockets in the star block, rotate 5 the spindle to throw the switch and then permit the arm to seat in the next socket.

The construction and operation of these several parts is well known and is described in detail, in the above mentioned patent. 10 Briefly stated, the switch can be thrown manually upon releasing the arm from the star block. The throw is absolutely positive for hand operation and the adjustment is such that upon completion of the throw 15 the arm will seat itself in the next adjacent socket, thus locking the spindle to the safety device or automatic control mechanism.

When the parts are in this interlocked position and the switch is run through by a 20 locomotive on a car, the movement will be communicated through the spindle and arm to the star block, all of which will be rotated against the compression of the springs. If the star points pass the center line of the 25 rollers, the switch point will be completely thrown to the opposite rail, but, on the other hand, if the star points do not pass the center line of the rollers, then the switch point will be automatically returned to its original 30 position as soon as the locomotive or the car clears the switch.

Under exception circumstances, as a result of unusual jars, shocks or concussions caused either by train movement or by external 35 causes, the arm 9 might free itself from the squared socket in the safety block, thus leaving the switch points loose on wild. In order completely to eliminate the possibility of such an occurrence I have devised means 40 for holding the arm positively but yieldingly in contact with the squared sockets of the star block, which will insure the seating of the arm when the switch is fully thrown, and incidentally apprise the switchman that 45 the parts are in their locked safety position through the noise made by the arm seating itself in the squared socket under pressure.

This is accomplished by interposing resilient means between the arm and a relatively 50 stationary portion of the switch stand. In the present embodiment of my invention the arm on the side of the spindle opposite the pivot point is enlarged to provide room for a recess or pocket 13. On the side of the 55 spindle opposite the hinge or pivot the block 10 is provided with an extension or abutment 14 directly above the pocket or recess formed in the arm. A spring 16 normally under considerable pressure is then inserted 60 in the recess and bears against the bottom of the recess and the abutment. That portion of the spring adjacent to the abutment and extending above the normal level or top of the arm is protected and enclosed by 65 means of an approximately vertical flange

or apron 15 which preferably is formed integral with the arm itself. The apron may also be provided with a horizontal ledge or flange 17 to engage with or overlap the abutment 14, thus completely enclosing the 70 spring and preventing tampering therewith.

Preferably also the abutment is provided with a lug 18 having an eye 19 formed there-in to receive suitable fastening means such as a padlock so the arm may be held permanently in its adjusted position. 75

By means of this arrangement I have provided a simple, compact and self-contained mechanism which holds the spindle and the arm in engagement with the automatic 80 safety means under a constant but yielding pressure sufficient to counteract any concussions or jars to which the switch may be subjected. A relatively stiff spring may be used without increasing appreciably the 85 amount of effort required to raise the arm preparatory to manual operation of the switch but which will cause the arm to snap back into its socket under sufficient pressure to make a noise that will apprise the switchman when the switch has been completely thrown. The spring is entirely enclosed so that accidental misplacement thereof or malicious tampering therewith is impossible. 90

Although I have shown and described a 95 preferred arrangement and combination of parts embodying my invention it is obvious that numerous changes and modifications may be made therein without departing from the spirit and scope of the invention, 100 provided the means set forth in the following claims be employed.

Having thus described my invention, I claim:

1. In a switch stand the combination of 105 a spindle operatively secured to a switch point, an arm pivoted to the spindle and movable therewith, a bearing for the spindle provided with a socket to receive said arm, an abutment rigid with the spindle above 110 the arm, and a spring between said arm and abutment normally to hold the arm in said socket.

2. In a switch stand the combination of 115 a spindle, an arm pivoted at one side of the spindle and projecting beyond the opposite side of the spindle and provided with a recess in said projecting portion, an abutment rigid with the spindle above said recess, a spring mounted in the recess and engaging 120 said abutment, and means on the arm enclosing said spring.

3. In a switch stand the combination of 125 a member rigid with a switch point and movable therewith, an arm pivoted to the member and having vertical movement relative thereto, said arm being adapted to interlock with a relatively stationary portion of the switch stand, an abutment on the spindle and yielding means between the arm 130

- and the abutment to hold the arm in its lowermost position.
4. In a switch stand the combination of a spindle operatively connected with a switch point, an operating arm pivoted to said spindle and having vertical movement with respect thereto and yielding means engaging said arm normally to hold the same against vertical movement.
- 10 5. In a switch stand the combination of a spindle operatively connected to the switch points, manually controlled means for actuating said spindle, means to control automatic movement of said switch points, an interlocking member between said spindle and said automatic control means and means for yieldingly holding said member in its interlocking position.
6. In a switch stand the combination with a movable arm operatively connected with the switch points, a member on said switch stand provided with means to interlock with the arm and resilient means positioned between the arm and a relatively stationary portion of the switch stand to hold the arm in interlocking position.
- 20 7. In a switch stand a spindle operatively connected to the switch points, an arm operatively connected to the spindle to rotate the same and throw the switch points, and yielding means between the spindle and arm to hold the arm yieldingly against movement relative to the spindle.
- 25 8. In a switch stand the combination of a spindle operatively connected to a switch point, a block stationary on said spindle, a spring seat integral with said block on one
- side thereof, an operating arm pivoted to said block on the opposite side thereof and a spring between said spring seat and said arm.
9. In a switch stand the combination of a safety device comprising a bearing block provided with a socket, a spindle mounted in said bearing block rotatable independently thereof, means securing said spindle to a switch point, an arm pivoted to said spindle and having movement into and out of engagement with said socket, said arm being provided with a recess, an abutment on said spindle above the arm, a spring mounted in said recess and engaging said abutment, and a flange on said arm enclosing the spring and overlapping said abutment.
- 40 45 50 55 60 65 70
10. In a switch stand the combination of means to control automatic throwing of the switch comprising a star block provided with a spindle bearing, said block having a plurality of sockets in the top thereof, a spindle mounted in said bearing and rotatable independently thereof, an arm pivoted to the spindle to move into and out of engagement with said sockets, said arm having a recess formed therein, a spring abutment rigid with the spindle arranged above said recess, a spring seated in said recess and engaging said abutment and a lug on said abutment provided with an eye extending above said arm.

Signed at Hillburn in the county of Rockland and State of New York, this 27th day of May, A. D. 1921.

WILLIAM C. KIDD.
